C. ABOS.
SPARK ARRESTER.

No. 11,057.

Patented June 13, 1854.

UNITED STATES PATENT OFFICE.

CASIMIR ABOS, OF NEW BRUNSWICK, NEW JERSEY.

SPARK-ARRESTER.

Specification of Letters Patent No. 11,057, dated June 13, 1854.

To all whom it may concern:

Be it known that I, CASIMIR ABOS, of New Brunswick, in the county of Middlesex and State of New Jersey, have invented a new and useful Improvement in Spark-Arresters; and I do hereby declare that the following is a full, clear, and exact description of the same, reference being had to the accompanying drawings, forming part of this 10 specification, in which—

Figure 1, is a horizontal section of a spark arrester with my improvements. Fig. 2, is a vertical central section of the same as in operation.

15 Similar letters of reference indicate corresponding parts in both figures. This invention relates to a new manner of constructing locomotive spark arresters, whereby the liability of the sparks escaping, 20 is greatly lessened, the draft space increased, and the greater portion of the sparks can be returned or conducted back into the fire box or chamber, so as to be consumed. This latter object being effected by the action or 25 pressure of the exhaust steam that brought them up out of the fire chamber.

To enable others skilled in the art to make and use my invention, I will proceed to describe its construction and operation.

30 A, represents the outer conical "stack" or chamber, mounted on the fire box, B, the top of the stack, A, is made concave, and has a central draft passage, C. D, is a taper pipe extending down from the passage, C, into 35 the central conducting or return pipe, E, as represented—this pipe prevents the sparks passing out directly through the passage, C, as will be evident from the drawing.

E, is the central conducting pipe, made 40 flaring at its upper extremity, and having a yielding or hinged self-adjusting valve, F, at its lower curved end—this pipe is sustained and kept in place by the stays, G, G; its object is to receive and conduct the sparks 45 back into the fire chamber, as fast as they rise to the top of the stack.

The stack is intended to be made on the most approved plan, and its deflecting sur-

face so situated or arranged, that the sparks will not fail to be deflected into the flaring 50 mouth of the central pipe E.

H, is an annular space formed between the outer periphery of the pipe, E, and the inner periphery of the stack, for the exhaust steam and sparks to pass through as they 55 pass to the top of the stack.

By examining the drawing, the operation may be clearly understood, it being as follows:—The exhaust steam and sparks rise through the space, H, and come in contact 60 with the top and sides of the stack, A, as indicated by the arrows, 1, and are deflected thereby, and caused to fall into the flaring mouth of the central pipe, E, and by their gravity and the pressure of the exhaust 65 steam, which causes the valve, F, to open, are made to pass down the pipe, E, and out through the valve, F, into the fire box, as indicated by the arrows, 2. As the sparks escape into the fire box or receptacle, and 70 during the temporary suspension of the pressure of the exhaust, the valve closes, as shown by dotted lines, and the remaining steam takes its course through the pipe, D, and escapes through the draft passage, C, as 75 indicated by the dotted arrows, 3. Owing to the valve closing automatically, all possibility of sparks, &c., returning through the pipe, D, is avoided.

By making the spark arrester without a 80 central smoke pipe, and side spark chamber, and having the stack itself serve as the smoke pipe, it may be obvious, the draft will be greatly increased.

What I claim as my invention, and desire 85 to secure by Letters Patent, is:—

The combination and arrangement of the draft pipe, D; central spark conducting or return pipe, E; hinged self closing valve, F, and stack, A, substantially as, and for the 90 purpose herein described.

CASIMIR ABOS.
